(57) **CLAIM**

The ornamental design for a device for carrying syringes as shown and described.

DESCRIPTION

FIG. 1 is a front perspective view of a device for carrying syringes showing our new design;

FIG. 2 is a rear perspective view thereof;

FIG. 3 is a front view thereof;

FIG. 4 is a rear view thereof;

FIG. 5 is a top plan view thereof;

FIG. 6 is a bottom plan view thereof;

FIG. 7 is a right side view thereof;

FIG. 8 is a left side view thereof;

FIG. 9 is an enlarged view of area 9 in FIG. 3;

FIG. 10 is an enlarged perspective cross-sectional view of FIG. 9;

FIG. 11 is an enlarged view of area 11 in FIG. 4;

FIG. 12 is an enlarged perspective cross-sectional view of FIG. 11; and,

FIG. 13 is a cross-section view of lines 13-13 in FIG. 9. The dashed lines depict portions of the device for carrying syringes that form no part of the claimed design. The dot-dash lines depict boundaries of the claim and form no part thereof. The dot-dot-dash lines depict the boundaries of the enlarged views that form no part of the claimed design.

1 Claim, 9 Drawing Sheets
